UNITED STATES PATENT OFFICE.

JAMES P. RODGERS, OF PITTSBURGH, PENNSYLVANIA, ASSIGNOR TO ELLIOTT COMPANY, OF PITTSBURGH, PENNSYLVANIA, A CORPORATION OF PENNSYLVANIA.

TUBE CLEANER.

Application filed April 9, 1924. Serial No. 705,209.

The present invention relates broadly to the art of tube cleaning apparatus, and more particularly to an improved form of cleaner for this purpose.

- 5 It is customary at the present time to construct tube cleaners having pivotally mounted cleaning elements adapted to swing outwardly, due to centrifugal force, and by a series of blows loosen the scale or deposit 10 on the inside of boiler tubes. It is one of the objects of the present invention to provide a cleaner of this general character in which the cleaning elements have a greater freedom of movement, permitting them to 15 assume any desired angular position relative to the longitudinal axis of the tube being cleaned.

In the accompanying drawings, there is shown for purposes of illustration only, one 20 embodiment of the present invention, it being understood that the drawings do not define the limits of the invention, as changes may be made in the construction and operation therein disclosed without departing 25 from the spirit of the invention or scope of the broader claims. In these drawings:

Figure 1 is a longitudinal sectional view through a cleaner embodying the present invention showing the parts in assembled relationship and in operative position on a driving member;

Figure 2 is a view similar to Figure 1, illustrating, however, the method of assembling the parts;

Figure 3 is a transverse sectional view on the line III—III of Figure 1, looking in the direction of the arrows;

Figure 4 is a transverse sectional view on the line IV—IV of Figure 1, looking in the direction of the arrows; and

Figure 5 is a transverse sectional view on the line V—V of Figure 1, looking in the direction of the arrows.

In accordance with the present invention, 45 there may be provided an elongated cleaner head 2 having a body portion of generally triangular section, as illustrated in dotted lines in Figures 4 and 5. At its forward end, the body is provided with a series of 50 uniformly spaced projections 3, preferably extending substantially radially of the body opposite the substantially flat sides thereof,

and each provided with an elongated bearing 4. Adjacent its rear end, the body is formed with a series of similar projections 5, having, however, slotted bearings 6 formed therein and extending through the ends thereof. Extending to the rear of the cleaner head is a substantially cylindrical portion 7, internally threaded to receive one 60 end of a suitable driving member 8 and externally shaped to slidably receive a keeper comprising a central hub 9 and a series of radiating arms 10, each provided with a bearing 11 similar to the bearings 4 in the 65 projections 3.

The cleaning elements preferably comprise a plurality of pins 12, corresponding in number to the projections 3 and having a 70 forwardly converging enlargement 13 on one end thereof. Each of these pins is adapted to receive a generally conically shaped cleaning element or cutter 14, adapted to rotate thereon and to directly abut at one end against the shoulder formed by the enlargement 13 and at its opposite end engaging a washer 15 surrounding the pin. The pin with the element 14 thereon is then moved longitudinally through one of the bearings 4, as clearly indicated in Figure 2, and during such movement has alternately supplied thereto washers 16 and cutting elements 17 which are also arranged to rotate thereon. The rear end of each of the pins is formed with diametrically oppositely disposed recesses 18 forming shoulders 18', adapted to engage the slotted bearings 6 in the projections 5. This permits a pin having the cutting elements in position thereon to be moved from the position illustrated in Figure 2 to the position shown in Figure 1. In this position, the recesses 18 prevent longitudinal movement and rotation of the pins, as will be clearly apparent.

After all the pins are in the position illustrated in Figure 1, the keeper is moved longitudinally of the projection 7 to engage the ends of the pins by threading the end of the driving member 8 into the projection. During this operation, a shoulder 19 on the driving member engages the keeper and moves it bodily inwardly from the position shown in Figure 2 to that illustrated in Figure 1. During this movement, a recess 20 in the

keeper is adapted to engage and receive a pin 21 on the cleaner head to lock the parts against relative rotation.

By reference to Figure 1 of the drawings, 5 it will be apparent that each of the pins 12 is capable of uniform bodily movement outwardly from the body of the cleaner head in a substantially radial direction under the influence of centrifugal force. At the same 10 time, the elongated spaced bearings cooperating with substantially opposite ends of the pins permit the same to assume different angular positions relative to the longitudinal axis of the tube being cleaned. These features have been found to be highly desirable 15 as opposite ends of the pins may move inwardly or outwardly different amounts as may be required by the conformation of the tube being cleaned, or all the cleaners 20 may be moved bodily outwardly uniformly under the influence of centrifugal force. During this operation, the bearings 4 and the keeper will limit the maximum outward or angular movement of the pins.

25 It will be apparent that the shape of the cleaner head may be changed to accommodate the same for use with a smaller or greater number of cleaning elements, depending upon the form of tubes with which 30 the cleaner is adapted to be used. Upon rotating the tool at high speed the cutters or cleaning elements will fly outwardly by centrifugal force and come into contact with the scale, dislodging it by a series of rapid strokes 35 in succession, the efficiency of the cleaner being proportioned to its speed and the quality of the scale.

I have found that the use of non-rotatable 40 pins is very desirable as the length of life of the cleaner is increased thereby. Where the pins are permitted to rotate, they tend to rapidly wear through their bearings. At the same time, as the pins are held against 45 rotation without the use of pins or rivets, they may be easily removed as desired.

The advantages of the present invention 50 arise from the provision of a cleaner head having cleaning elements which are capable of having a uniform or angular bodily outward movement.

Further advantages arise from the provision 55 of a cleaning head as disclosed herein, by reason of which the assembly of the component parts is facilitated.

55 I claim:

1. In a tube cleaner, a head, a cleaning element, means on the head for supporting the element to be bodily movable outwardly therefrom, the element having a recess in at 60 least one side thereof, and means on the head for cooperating with such recess for holding the element against movement axially of the head while in any operating position thereon.

56 2. In a tube cleaner, a head, a cleaning ele-

ment, means on the head for supporting the element to be bodily movable outwardly therefrom, the element having a recess therein, and means on the head for entering such recess and abutting against both sides 70 thereof for holding the element against movement axially of the head while in any operating position thereon.

3. In a tube cleaner, a head, a cleaning element, means on the head for supporting the element to be bodily movable outwardly 75 therefrom, the element having recesses in opposite sides thereof, and means on the head for cooperating with such recesses for holding the element against movement axially of the head while in any operating position thereon.

4. In a tube cleaner, a head, a cleaning element, and means on the head for supporting the element to be bodily movable 85 outwardly therefrom, the support having an outward extension, the element and the extension having cooperating portions adapted to interlock for holding the element against movement axially of the head while in any operating position thereon.

5. In a tube cleaner, a head, a cleaning element carrier, means on the head for supporting the carrier to be bodily movable 95 outwardly therefrom, the carrier having a recess therein and the head having a recess adapted to cooperate with the recess in the carrier to prevent both rotation of the carrier and movement thereof axially of the head when in any operating position thereon.

6. In a tube cleaner, a head, a cleaning element, means on the head for supporting the element to be bodily movable outwardly therefrom, a keeper for limiting outward movement of the element, the head and the keeper having recesses therein, means for insertion into such recesses to prevent relative rotation between the head and the keeper, and a driving element adapted to be connected to the head and having means 105 for engaging the keeper to maintain the keeper in place.

7. In a tube cleaner, a head, a cleaning element, means on the head for supporting the element to be bodily movable outwardly 110 therefrom, a keeper for limiting outward movement of the element, a driving means for the head rotatable relatively thereto to effect operative connection therewith, the driving means abutting against the keeper 115 when in operative position to maintain the keeper in place.

8. In a tube cleaner, a head, a cleaning element, means on the head for supporting the element to be bodily movable outwardly 120 therefrom, a keeper for limiting outward movement of the element, the head and the keeper having recesses therein, means for insertion into such recesses to prevent relative rotation between the head and the 125 keeper.

keeper, a driving means for the head rotatable relatively thereto to effect operative connection therewith, the driving means abutting against the keeper when in operative position to maintain the keeper in place.

9. In a tube cleaner, a head, driving means for the head rotatable relatively thereto to effect operative connection therewith, a cleaning element mounted on the head to be

movable outwardly therefrom, and a keeper 10 engaged by the driving means during such relative rotation and held in operative position thereby for limiting outward movement of the cleaning element.

In testimony whereof I have hereunto set 15 my hand.

JAMES P. RODGERS.
